his Atty's.

United States Patent Office.

WILLIAM M. KIRCHNER, OF PITTSBURG, PENNSYLVANIA, ASSIGNOR TO THE NATIONAL GLASS COMPANY, OF BELL AIR, OHIO.

Design No. 4,261, dated July 26, 1870.

DESIGN FOR GLASS-WARE.

The Schedule referred to in these Letters Patent and making part of the same

To all whom it may concern:

Be it known that I, WILLIAM M. KIRCHNER, of the city of Pittsburg, in the county of Allegheny and State of Pennsylvania, have invented a new and useful Design for Glass-Ware; and I do hereby declare the following to be a full, clear, and exact description thereof, reference being had to the accompanying drawings making a part of this specification, which represent a plan view of my improved design as applied to a section of the bowl of an article of glass-ware.

To enable others skilled in the art to make and use my improvement, I will proceed to describe it more fully.

A represents the central knob or stem of an article of table glass-ware, such as a bowl, fruit-dish, &c., and B the rim.

Around the stem or knob A I repeat the design shown, which consists of raised prismatic beads α α' , crossing each other half way, and meeting at their ends, so as to form oblong loops, and recrossing to form the repetition.

These beads inclose oblong surfaces b of frosted work.

Touching or intersecting each of these beads α α' ,

on the sides next the stem A, is a prismatic bead, c , inclosing a space of the form of a letter G, except that one C is reversed, so that the open sides of the two will correspond, and the ends of the beads meet.

The spaces d , so inclosed, are also frosted, as also are the diamond-shaped spaces d' , inclosed between the beads α α' and c .

From the beads c , on the sides next the stem A, a third arrangement of beads, e , springs off, so that their meeting ends shall point toward the stem A.

The diamond-shaped space e' included between the beads c and e , is also frosted, as shown.

This design may be repeated on any article of bowled glass-ware, around the stem, foot, or knob, or around on the outer face of a glass tumbler.

What I claim as my invention, and desire to secure by Letters Patent, is—

The design for glass-ware, hereinbefore described and shown.

In testimony whereof, I, the said WILLIAM M. KIRCHNER, have hereunto set my hand.

WILLIAM M. KIRCHNER.
